UNITED STATES PATENT OFFICE.

JOHN EDWARD THORNTON, OF WEST HAMPSTEAD, LONDON, ENGLAND.

MOTION-PICTURE-PROJECTING MACHINE.

Application filed February 1, 1927, Serial No. 165,228, and in Great Britain December 11, 1925.

This invention relates to improvements in motion picture projecting machines, one object of the invention being the provision of a means whereby it is rendered unnecessary to feed the film through the film-advancing mechanism and loop-forming portion of the projector, there being provided a leader strip which is attached to the reel and of sufficient length to project through the film-advancing means and the loop-forming portion so that it is only necessary to connect the film that is to be run through the projector to said leader strip, the reel-on reel being permanently mounted within the projector.

In the existing styles of apparatus, and practically all makes thereof, it is usual practice to first insert the spool carrying its store of film in the apparatus, to then draw off a portion of the film and thread it through the mechanism over, under, or around the various toothed sprockets and guide or pressure rollers, through the gate, and finally to attach it to the receiving reel, and to so adjust the length of film that a pair of free loops, each of the correct length, is formed, one above and one below the gate. This lengthy operation has to be carried out with care and precision, and has to be repeated each time the apparatus is re-loaded with a fresh supply of film. It is also the usual practice to detach and remove both the reel and spool, as well as the film, after use and to put in a new reel and spool prior to repeating the threading processes.

According to the invention, the apparatus is fitted with a rotary reel which is permanently located within the casing instead of being detachable and removable, as is the usual practice. To this reel is permanently fastened one end of a leader strip, which strip is of sufficient length to reach from the reel through the necessary film guide and feeding mechanism to form the necessary loops and present its end for connection to the end of the film which, in turn, is carried by the usual removable spool. By this means, it is unnecessary to produce the loops in the film by hand, as is the usual practice, and as this apparatus comes with the leader strip already positioned, an amateur can

operate the machine with very little instruction.

A similar leader strip is also affixed at one end to the loose spool and the film is joined at one end to the spool-leader and at the other end to the reel-leader so that the three parts form one line of strips as a continuous tape attached at one end to the loose spool and at the other end to the permanently fixed reel.

The two parts are connected together by any suitable convenient fastener, such as spring clip, hook, eye, button, key-slot, or the like, which will allow the parts to be quickly and reliably connected and easily disconnected.

The invention will be described with reference to the accompanying drawings:—

Fig. 1 is a diagrammatic side view showing the permanently fixed reel with its leader strip attached to the end of the film wound on the spool.

Fig. 2 is a perspective view of the permanently fixed reel, the reel leader, the film, and the loose spool.

Fig. 3 is a view similar to Figure 2 showing a film leader permanently attached to the end of the film.

Fig. 4 is a perspective view of the loose spool, loose-spool leader, film cemented to the loose spool leader and permanent reel.

Fig. 5 is a view similar to Figure 4 but showing the film detachably connected to the loose spool leader.

Figs. 6 and 7; Figs. 8, 9, 10 and 11; Figs. 12 and 13; and Figs. 14 and 15 illustrate different ways of attaching the end of the film to the leader strip.

The kinematograph projector, camera or printing apparatus is provided with a winding-on-reel A permanently located in the apparatus. A leader strip B sufficiently long to extend through the feed mechanism of the machine is permanently fastened at one end to a reel A which preferably is permanently fixed to the winding shaft of the apparatus, and is provided at the other end with means by which it may be readily affixed to the end of the film C carried on the loose spool D. The leader strip B may be made of linen tape or other suitable mate-

rial of sufficient strength, such as a double or triple layer of paper or paper and linen or film-material combined and preferably is treated to make it fire-proof.

5 Thus when the film C is joined at one end to the spool-leader B¹ and at the other end to the reel leader B, the three parts form one continuous tape attached at one end to the spool and at the other end to the permanently fixed reel A.

10 As shown in Fig. 1, the winding-on reel leader B is made of sufficient length to reach from the permanently fixed reel A through the sprocket wheels e, gate E and sprocket 15 wheels e¹ of the apparatus to the spool D and also to allow the necessary slack or surplus to form the usual loops b, b' between the gate and the feed sprockets.

15 When the reel A and the leader-strip B are mounted in the apparatus, the leader strip is threaded in the usual way over the sprocket wheels e, through the gate E and over the sprocket wheels e¹, a loop b being formed between the sprockets e and the gate 20 E, and a second loop b' being formed between the gate E and the sprockets e¹. The reel A after once being placed need not be removed from the apparatus.

25 The spool leader strip B¹ is affixed at one end to the spool D in any usual way and at the other end is attached to the film C.

30 In operation, when the free end of the reel-leader B is connected to the film and the machine set into motion, the leader-strip 35 itself will soon pass completely out of the sprocket e', gate mechanism E, and sprocket e and wind on to the reel A; the film C itself follows and eventually also finds its way to the reel A. But during the whole of 40 these operations the loops b, b¹ are maintained whatever part of the strip happens to be in position at the gate.

45 When the film C has been run through the apparatus and the spool-leader B¹ appears in the apparatus the motion is reversed and the film C is wound back on its original spool D following the spool-leader B¹ in the process, and finally bringing the reel-leader B back into the apparatus with the 50 loops b, b¹ still maintained as before. The film is then detached from the reel-leader B, whereupon the spool D can be removed and another spool and film substituted so that, after the first threading, no further threadings are necessary.

55 The film C may be attached directly to the reel-leader strip B as shown in Fig. 2 or indirectly by a film leader strip c cemented on to the end of the film C as shown in 60 Fig. 3.

65 Any suitable fastening device may be employed for attaching the film C or leader strip c to the leader-strip B. A number of suitable fastening devices by which the films are joined are illustrated in Figs. 6 to 15 of

the drawings, but the invention is in no way limited to such devices and any other form of fastening device may be employed as is found desirable.

70 In the form shown in Figs. 6 and 7 two holes b² are formed in the end of the leader-strip B and two corresponding holes c² in the end of the film C, the two ends being joined together by a wire staple c passed through the holes. 75

75 As shown in Figures 1, 2 and 3, a T-shaped tongue c³ is formed upon the leader B, while the T-shaped aperture b³ is formed upon the film, the same being assembled as shown in Figure 1 to connect the two together. 80

85 In the form shown in Figs. 5, 8, 9, 10 and 11 a substantially T-shaped tongue c³ is formed on the end of the film and a substantially T-shaped aperture b³ is formed in the end of the leader-strip B the two being joined together by inserting the tongue c³ in the aperture b³.

90 In the form shown in Figs. 12 and 13 a bent wire b⁵ is hingedly secured at the end of the leader-strip B by turning the end of the latter over said wire and cementing it to the strip, the end of the film C being also bent over and cemented to form eyes c⁶ to receive the ends b⁵ of the wire b⁵ which are sprung into the eyes to attach the film to the leader. 95

100 In the form shown in Figs. 14 and 15 hinge members are formed by bending over the end of the leader B and loop b⁷ thereon and by bending over the end of the film C to form two loops c⁷, the loop b⁷ fitting between the loop c⁷ and hinged together by the pintle c¹.

105 Any other form of fastening device may be employed but such device should be thin, flexible, and easily operated.

110 Usually there is no need for a fastener at the spool end of the film to be rewound upon the removable spool, as the film C can be permanently cemented to the leader B¹ as in Fig. 4 or a film leader c¹ can be cemented to the spool-leader B¹ since the spool is removable from the apparatus. If desired, however, a fastening device, such as employed for affixing the film to the winding-on reel leader, may be used for attaching the film to the spool leader. 115

120 The invention is useful in all projectors where it is customary to rewind the film through the apparatus after each exhibit.

125 What I claim as my invention and desire to protect by Letters Patent is:—

130 In a motion picture projecting machine, a permanently mounted rotating wheel, a detachable spool and film-advancing and loop-forming means interposed between the reel and spool, and a film attaching and guiding leader strip attached permanently at one end to the permanent reel and of sufficient length

to reach through and be threaded through or detached remains connected to the reel and beyond the film-advancing and loop-forming means to thus form the necessary means of the machine. 10
loops, and means upon the free end thereof In testimony whereof I have hereunto set
5 for attachment to the film to be fed through my hand.
the projecting machine, whereby the leader strip, when the film is either being attached
